UNITED STATES PATENT OFFICE.

OSMER W. ROPER, OF VINELAND, NEW JERSEY.

ARTICLE CARRIER.

Application filed October 24, 1921. Serial No. 510,068.

To all whom it may concern:

Be it known that I, OSMER W. ROPER, a citizen of the United States, residing at Vineland, in the county of Cumberland and

5 State of New Jersey, have invented certain new and useful Improvements in Article Carriers, of which the following is a specification, reference being had to the accompanying drawings.

10 This invention relates to article carriers and particularly to a carrier used for the shipment of eggs.

It is well known that the rectangular form of carrier, on account of its construction, is 15 not practical for the reason that the fillers used in the egg box for the reception of the eggs, fit closely to the inner walls of the box, thereby disposing a portion of the egg in contact with the inner wall so that in the 20 event of the carrier coming in contact with an object, or receiving a sudden jar, there is danger of the egg breaking, and unquestionably so if the wall of the carrier is forced inwardly. Furthermore, the fillers 25 for the container are of special construction and therefore must be furnished from the factory when a new supply is necessary.

It is, therefore, an object of the invention to provide a carrier which is circular in 30 form to eliminate corners and to facilitate handling of the carrier.

It is another object of the invention to provide a device of this character which, in view of its circular form, is spaced from 35 the fillers or receptacles in which the eggs are disposed within the carrier so that damage to the wall of the carrier by an object which tends to mutilate the wall will not cause damage to the eggs.

40 It is another object of the invention to provide a carrier of this character circular in form and constructed to receive a conventional form of rectangular individual egg box, the sides and ends of the box being spaced from the wall of the container in view of their rectangular form.

It is also an object of the invention to provide a carrier of this character including novel fastening and clamping means in 50 the form of a bail hasp which is hinged to one side of the carrier and adapted to extend over the cover and into engagement with the keeper on the opposite side of the carrier, suitable fastening means being provided to prevent disengagement of the hasp from the cover.

It is still a further object of the invention to provide a carrier of this character including a cover having spaced guide members and a handle, the spaced guide members being adapted to receive the ends of an address card, the handle being adapted to project through the card, the hasp of the carrier being also provided with an opening through which the handle of the cover extends, 60 whereby the hasp serves to maintain the address card in engagement with the cover without the use of additional securing means.

With these and other objects in view, the 70 invention consists in the improved construction and arrangement of parts to be herein-after more particularly described, fully claimed and illustrated in the accompanying drawings, in which:

Figure 1 is a transverse sectional view of a carrier constructed in accordance with an embodiment of the invention, and showing the cartons within the carrier;

Figure 2 is a top plan view of the carrier;

Figure 3 is a top plan view showing the bail hasp released, a portion of the address card being broken away to show one of the guides; and

Figure 4 is a top plan view showing the 85 bail hasp member applied and the cover removed.

Referring to the drawings, 5 designates a container or carrier constructed preferably of metal and being circular in form. This 90 container may be constructed in various sizes to hold two dozen, three dozen, four dozen or more eggs. Its construction also permits it to be used for conveying articles of food other than eggs such as cheese, butter, etc., as the receptacles for holding the eggs are not secured in the container. By the circular formation of the container, all corners and like projecting parts are eliminated, thus facilitating the handling of the 100 device and eliminating the possibility of the carrier, should it be roughly handled, from landing on any of the corners and thereby jarring the contents of the carrier to such an extent as to damage the same. With the 105 circular wall of the carrier, if the same is placed on its side, there is no danger of jolting.

A cover 6 is provided for the carrier, said cover being circular in form and having a 110 depending annular flange 7, the edge of said flange being curled to form a bead 8. Dis-

posed centrally of the cover is a socket member 9, open at its ends for the reception of a bail or handle 10, the handle being slightly greater in length than the length of the 5 socket member, but large enough to receive the hand of a person. Disposed in spaced relation to the socket member 9, and on each side of the socket member, is a guide member 11, said guide member consisting of a strip 10 of material having one edge thereof turned back upon said strip to provide a flange 12, the flanges 12 of each member being turned or extended toward each other. The ends 15 of each of the guide members 11 are open. The purpose of the particular arrangement of the handle and the guide members, is to receive an address card 13, said card being of a length to extend transversely of the cover so that its ends will extend beneath the flanges 12 of the guide members. 20 The intermediate portion of the card 13 is provided with a longitudinal slot 13^a which extends transversely of the card, said slot being of a length to permit the insertion 25 of the bail and socket member of the cover. By this means, the socket member and bail project above the card and limit lateral movement of the card to a large extent so that accidental disengagement is impossible. 30 With this arrangement, the socket member and bail serve as holding means for the card by cooperating with the guide members 11, the guide members serving to protect the ends of the card. 35 In order to fasten the cover to the carrier, novel fastening means are provided in the form of a bail hasp 14, said hasp consisting of a length of material similar to the material used in the construction of the carrier, having its longitudinal edges beaded as at 15 to reinforce the bail hasp. The end portions 16 and 17 are extended at right angles to the strip, the distance between the junction of said end portions 16 and 17 with 40 the strip being slightly less than the distance between the bead 8 of the cover at opposite points so that when the hasp is applied to the cover it is slightly sprung to produce a clamping action. Carried by one side of the 45 container or carrier 5 is a plate 18 having a knuckle 19, while formed on the extremity of the end 17 of the bail hasp is a plurality of knuckles 20, the knuckles 19 and 20 being adapted to register for the reception of 50 a pintle 21 by means of which the bail hasp is hinged to the carrier. The end portion 16 is provided with an opening 22 adapted to receive a keeper 23 carried by the opposite side of the container or carrier 5. Any suitable means, such as a lock or keyring, may 55 be used to fasten the bail carrier to the container. The intermediate portion of the strip 14 is provided with a longitudinally extending slot 23^a corresponding in length to the 60 slot 13^a of the address card and through 65

which the socket member 9 and bail 10 are intended to extend. By this means, the bail hasp not only serves to hold the cover in engagement with the carrier, but serves to fasten the address card thereto, in view of 70 the clamping action above described. The opening 24 in the keeper 23 is positioned so that when the lock or fastening means is applied it will urge the end portion 16 of the bail hasp member inwardly and complete the clamping action of the bail hasp member. 75

When the device is used for the shipment of eggs, the cardboard card or pasteboard plate 25 is placed in the bottom of the carrier. If the carrier is constructed for two dozen eggs, two cardboard boxes or cartons of conventional form are used, said cartons being similar to those used by grocers and poultry dealers for packing eggs so that a 80 supply can be maintained at any place in view of their popularity, thus eliminating the necessity of sending to the manufacturer. One of these rectangular cartons 26 filled with eggs is placed in the container on the plate 25. A cardboard or pasteboard plate 27, corresponding in diameter to the diameter of the carrier is placed upon the carton 26. Another rectangular carton 28 is placed upon the cardboard plate 27 and a third cardboard plate 29 is placed upon the carton 28. The last mentioned plate is intended to fit snugly within and beneath the rolled or beaded edge of the container so as to prevent unnecessary movement of the 85 egg cartons within the carrier. The cover 13 is then applied, and the hasp member swung over the handle and into engagement with the keeper. 90

From the foregoing it will be readily seen 105 that this invention provides a novel form of egg carrier capable of being used by anyone in view of the fact that the conventional form of rectangular egg cartons may be used in connection with the carrier. Furthermore, the circular formation of the carrier and rectangular formation of the cartons prevents damage to the eggs even when the carrier is dented, as the sides and ends of the cartons are spaced a considerable distance from the walls of the carrier. Furthermore, in view of the use of the conventional form of carton, it is not necessary to place any projection or shelves within the carrier so that the entire interior may be 110 used for shipping butter, fruit, or in fact, any article of food, handling of the carrier being facilitated by the novel form of bail 115 10. Accidental disengagement of the cover is impossible, in view of the substantial form 120 of bail hasp. 125

What is claimed is:—

1. A carrier of the character described comprising a circular container, a cover for said container, spaced guide members car- 130

ried by the cover adjacent its edges, a movable handle member carried by the intermediate portion of the cover, an address card having a central slot adapted to receive the handle, the ends of said card being disposed within the guide members, and means carried by the container for engagement with the cover and the card, to prevent disengagement of the cover and card with respect to the container.

2. A carrier of the character described comprising a circular container adapted to receive rectangular cartons, a cover for the container, a socket member carried by the central portion of the cover, a bail having its ends disposed within said socket, a bail hasp member having one end portion thereof hinged to one side of the container, the major portion of said hasp member being adapted to extend over said container, the intermediate portion of said major portion having a slot adapted to receive said socket member and bail, the opposite end of the bail hasp member being adapted to extend in parallel relation with the opposite side

of the container, a keeper projecting from the last mentioned side of the container, and means for locking the last mentioned end of the bail hasp member to the container through the medium of the keeper.

3. A carrier of the character described comprising a circular container, a cover for said container, said cover having a depending flange, the edge of the flange being beaded outwardly, a bail hasp member having its end portions disposed at right angles to the major portion of said bail hasp member, one of said end portions being hinged to the container, the opposite end portion having a slot for the reception of a keeper carried by the opposite side of the container, said end portions being urged over the beaded cover and inwardly upon the application of fastening means to the keeper whereby the hasp member firmly clamps the cover to the container.

In testimony whereof I hereunto affix my signature.

OSMER W. ROPER.
